[57] CLAIM

The ornamental design for a shoe sole, as shown and described.

DESCRIPTION

FIG. 1 is a bottom plan view of a shoe sole illustrating my new design;

FIG. 2 is a right side elevational view thereof;

FIG. 3 is a left side elevational view thereof;

FIG. 4 is a front elevational view thereof;

FIG. 5 is a rear elevation view thereof; and,

FIG. 6 is a perspective view thereof.

The broken lines shown in FIGS. 2, 4, and 5 are environmental structure only and do not form part of the claimed design.
